UNITED STATES PATENT OFFICE.

DANIEL L. LEWIS, OF BRADFORD, PENNSYLVANIA.

OIL-WELL-TUBING CLAMP.

SPECIFICATION forming part of Letters Patent No. 277,142, dated May 8, 1883.

Application filed August 21, 1882. (No model.)

To all whom it may concern:

Be it known that I, DANIEL L. LEWIS, a citizen of the United States, residing at Bradford, in the county of McKean and State of Pennsylvania, have invented certain new and useful Improvements in Oil-Well-Tubing Clamps; and I do hereby declare the following to be a full, clear, and exact description of the invention, such as will enable others skilled in the art to which it appertains, to make and use the same.

This invention relates to tubing-clamps and elevators which are used for lowering the tubing of an oil-well into the well and withdrawing the same therefrom.

The object, purpose, and scope of the invention will appear from the following description and claims.

My device is illustrated in the accompanying drawings as follows:

Figure 1 is a perspective view, showing the clamp closed. Fig. 2 is a top or plan view of the clamp closed, but with the locking-key removed, so as to show cavities into which the key fits. Fig. 3 shows the clamp wide open, and is an elevation of its inner faces. Fig. 4 is a vertical section on the line $z z$ in Fig. 1, a section of tubing being shown in elevation, the only parts cut by the line of section being the hinge and the locking-key. Fig. 5 is a vertical section on the line $x x$ in Fig. 2. Fig. 6 is a like view on the line $y y$ in Fig. 2. Fig. 7 is a perspective view of the locking-key detached from the clamp.

The invention relates to the devices for locking the parts of the clamp together when in place around the tubing, and to the form of the opening in which the tubing is held. As the office and purpose of a tubing clamp and elevator are well known, I need not here refer to them.

The two parts of the clamp are generally held together, when the clamp is in position upon the tubing, by so placing the suspending-links that when they are in position for suspending one of them will embrace the two handles, and thus hold the clamp together. Another method is to have a separate latch-link which will turn up and embrace the two handles. There have been various other devices made for holding the two parts of the clamp

together. In fact, the means for so doing constitute the gist of most of the various patented devices.

The essential requisite of a clamp is that the means for fastening the two parts together when it is in position on the tubing shall be capable of easy manipulation, and shall hold the parts together surely, and thus make the clamp both easy to apply and disconnect, and be perfectly safe while applied.

$A' A^2$ are the two parts of the clamp. They are provided with handles $a' a^2$.

B is the locking-key, and is provided with a handle, B' . The form of this key is shown in Fig. 7. It has on each side a lip, $b' b^2$, one of which, b' , goes the whole length, while the other, b^2 , only goes about half the length. On the back the key is somewhat wedge-shaped.

The two parts of the clamp near the handles are each provided with L-shaped grooves, which form the key-socket. The top face of the parts $A' A^2$ are also cut away somewhat about the mouth of the key-socket, so as to allow the key-head to drop down about flush with the upper surface of the clamp. The form of the key-socket, as made by the two L-shaped grooves, is clearly shown in Fig. 2, and it will be seen, by observing Fig. 7, that the key there shown will fit into the socket and that when it is in place the jaws of the clamp cannot be opened. It will be obvious to any one that the precise form of the key and socket shown may be greatly varied and yet obtain a form which will serve equally well to lock the two parts or jaws together when the key is in place. It is desirable that this key be so constructed that it need not entirely leave the socket in one of the jaws, but that it be so constructed as to always be in position for immediate use. To this end I have made the lip b^2 shorter than the lip b' . Hence when the key is lifted up in the socket high enough to bring the bottom of the lip b^2 above the top of the clamp the jaws can swing open. To prevent the key from being drawn out farther than is necessary to allow the jaws to open, I put on the outside of the lip b' a pin, c , and the groove g is provided with a groove, e , running part way to the top. This prevents the key from being pulled out. The pin c has to be put in place, after the key is in the socket,

by passing it through the hole *j*. (For this latter construction see Fig. 5.) When the elevator is in use the key should be so held in place that it cannot jump out or be knocked out accidentally. When in use lifting or holding a vertical line of tubing the collar or thimble on the tubing rests on the top of the jaws, (see Fig. 4,) and when in this position the said collar comes in contact with a beveled face, *n*, on the key-head. The opposite side of the key-head has a bevel, *b*, and the top of the grooves *g g'* are made with an overhanging ledge, *a*, and the pressure of the collar on the tubing on the beveled face *n* drives the bevel *b* back under the ledge *a*, and makes it impossible for the key to escape or be taken from its socket until the clamp is relieved of the weight of the tubing.

In the operation of drawing or lowering tubing it often happens that it is most convenient to put the clamp onto the tubing some distance below the collar *N*. In that case the links, the hook on the tackle-block, and the tackle-block have to lie on one side of the tubing, and when they begin to draw up the draft is sidewise slightly on account of their position, and this tends to bind the clamp upon the tubing and not permit it to slip up freely to the collar, where it must rest before it is safe to lift the tubing. In order to avoid this binding, I make the opening *D* in the clamp tapering, as shown in the drawings, and this permits the clamp to slip along the tubing easily when it drawn upon sidewise, as is the case in the instance above referred to. The taper above referred to is represented by the dotted line *D'* in Fig. 2, and is seen clearly in Fig. 4.

It will be observed that the grooves forming the key-socket are slightly at an angle to a vertical line, and, from the position of the key when drawn up, as is shown by dotted lines in Fig. 3, that the key, when drawn, moves away from the tubing. The object of this is to allow the key to be drawn as soon as the collar *N* on the tubing is slightly off of it, and not have to wait until the clamp is as far below the collar as the key moves upward. In other words, the key gets back out of the way of the collar when moved upward slightly.

The form and construction as shown in the drawings I consider preferable; but I do not wish to be limited to it, as it is susceptible of many variations. As has been already pointed out, the form of the key and the key-socket may be varied. In place of grooves on the inside faces to form a key-socket, the two jaws may be ledged at that point, so as to lap over each other, and with a key-opening in each ledge and a simple pin for a key, passing first through the ledge of one jaw and then that of the other, in a manner not unlike the pintle at the hinge. Such a construction, with proper means for keeping the pin from falling out,

would serve in a manner substantially the same as the construction shown.

65

What I claim as new is—

1. In an oil-well-tubing clamp, the combination, with the two parts or jaws forming the clamp-body, of a vertically-acting pin or key carried by one of the jaws and engaging within a key-socket formed partly in one and partly in the other jaw, substantially as shown and described.

2. In an oil-well-tubing clamp, the combination, with the two parts or jaws forming the clamp-body, of a vertically-acting pin or key carried by one of said parts and engaging within a key-socket formed partly in each of said parts and so inclined to a vertical line that the pin or key as it moves up will recede from the tubing held by the clamp, substantially as shown and described.

3. In an oil-well-tubing clamp, the combination, with the two parts or jaws forming the clamp, of a vertically-acting key, *B*, having lips or flanges *b' b²*, carried by one of said parts and engaging within right-angled or L-shaped recesses *g g'* on the inner faces of each of said parts, substantially as and for the purposes mentioned.

4. In an oil-well-tubing clamp, the combination, with the two parts or jaws forming the clamp, of a vertically-acting key, which engages within a key-socket formed partly in one and partly in the other of said jaws, and provided with a head which, when the key is in place, will approach so near the well-tubing as to be impinged upon by the collar on said tubing, substantially as and for the purposes set forth.

5. In an oil-well-tubing clamp, the combination, with the two parts or jaws forming the clamp, having in their abutting faces recesses forming a key way or socket, which recesses are provided with a ledge or shoulder *a*, of a vertically-acting key working in said recesses, and having a head beveled on opposite sides, as shown at *n* and *b*, substantially as and for the purposes set forth.

6. In an oil-well-tubing clamp, the combination, with the two parts or jaws forming the clamp, of the recesses *g g'* and *e*, the key *B*, with lips or wings *b' b²*, and the pin or lug *c*, substantially as shown.

7. In an oil-well-tubing clamp, the surfaces of the jaws which come against the tubing made inclined, so that the opening formed by said surfaces shall be tapering, as and for the purposes set forth.

In testimony whereof I affix my signature in presence of two witnesses.

DANIEL L. LEWIS.
